FLOAT-SWITCH ASSEMBLY

Dennison H. MacDonald, East Haven, Conn., assignor to Revere Corporation of America, Wallingford, Conn., a corporation of Connecticut

Application May 8, 1951, Serial No. 225,113

5 Claims. (Cl. 200—84)

1

This invention relates generally to float switches, and more particularly to float switch assemblies of the type used in tanks to control the filling thereof.

It is an object of the present invention to provide a float switch assembly of this type which is of rugged and condensed construction and unimpaired by even strong liquid currents thereagainst, and which is nevertheless highly reliable in operation and sensitive in action, thereby to adapt the float switch assembly especially, though by no means exclusively, for installation in a liquid tank to exercise a safe and reliable control over the charging of the latter with liquid even when it is forced therein under considerable pressure or at a high flow rate, or both.

It is another object of present invention to provide a float switch assembly of this type which will remain unimpaired even when subjected to shock or vibration, thereby to render the float switch assembly particularly suited for installation in fuel tanks for air, sea or land carriers, which are frequently subjected to these conditions.

It is a further object of present invention to provide a float switch assembly which lends itself not only to efficient mass production at relatively low cost, but to ready installation in a tank as well.

Other objects and advantages will appear to those skilled in the art from the following, considered in conjunction with the accompanying drawings.

In the accompanying drawings, in which certain modes of carrying out the present invention are shown for illustrative purposes:

Fig. 1 is a part-sectional and part-elevational view of an installed float switch assembly embodying the present invention;

Fig. 2 is a section taken on the line 2—2 of Fig. 1;

Fig. 3 is a fragmentary section taken substantially on the line 3—3 of Fig. 2, with certain parts shown in elevation;

Fig. 4 is a fragmentary section taken substantially on the line 4—4 of Fig. 1.

Fig. 5 is a fragmentary section taken on the line 5—5 of Fig. 1 and

Fig. 6 is a fragmentary section similar to Fig. 3, and showing a modification of the float switch assembly.

Referring to the drawings, and more particularly to Figs. 1 and 4 thereof, the reference numeral 10 designates a float switch assembly which is shown installed in a liquid tank T. The

2

float-switch assembly 10 comprises a casing 14, a switch control unit 16 and a switch 17.

The casing 14 is, in the present instance, in the form of a cylindrical shell which is closed at its bottom. Suitably mounted in the casing 14, as by spot-welding, for instance, is a bracket 18 which may be generally rectangular in outline, and of a width to permit the unimpeded flow of a liquid L through the casing 14 (Figs. 2 and 4). A cover 20, which closes the open bottom of the casing 14, may conveniently be held in position by a screw 22 which is threadedly received by the bracket 18. Provided on top of the casing 14 is a cap 24 which is sealed from the interior of the casing 14 by an interposed partition 26. A peripheral margin of the partition 26 is conveniently interposed between and welded or otherwise secured to out-turned flanges 28 and 30 of the cap 24 and a sleeve 32, respectively. The sleeve 32 is, in turn, pressfitted on or otherwise secured to a top length of the casing 14, so that the latter forms with the cap 24 and the interposed partition 26 an integral unit. The sleeve 32 on the casing 14 is provided with an out-turned flange 34 which is suitably secured, as by rivets 36, to the top wall 38 of the tank T, the major part of the casing 14 extending into the interior of the tank T through an aperture 39 in the top wall 38 thereof. The casing 14 is, within the confines of the tank T, provided with one or more inlets 40 and one or more outlets 42. As best shown in Figs. 1 and 4, the inlets 40 are provided near the bottom end of the casing 14, while the outlets 42 are provided in the casing 14 in close proximity to the top wall 38 of the tank T.

The switch-control unit 16 is pivotally mounted on a support 50 which may be mounted on the bracket 20 by bolts 52 or the like. The support 50 is in this instance, U-shaped as shown in Fig. 5, and threadedly receives in its opposite legs 54 and 56 screw-type studs 58 and 60, respectively, the adjacent ends of which are conically recessed to serve as needle bearings for the conical ends 62 and 64, respectively, of a pivot 66 on which an arm 68 of the switch-control unit 16 is firmly mounted. The studs 58 and 60 may individually be turned for adjustment, while nuts 70 and 72 serve to lock the studs 58 and 60, respectively, in correctly adjusted position to the support 50. One end of the arm 68 of the switch-control unit 16 carries a permanent magnet 74, while a substantial length of the arm 68 on the opposite side 55 of the pivot 66 is enlarged to form a float-portion

76 which in this instance is a solid and integral part of the arm 68.

The pivot-axis of the switch-control unit 16, comprising the arm 68 with the float-portion 76 thereof and the permanent magnet 74, passes through, or substantially through, the center of gravity of said unit 16 so that the latter will in any angular disposition thereof be in neutral equilibrium.

Suitably mounted in an aperture 80 of the partition 26 in the casing 14 is the open end of a tubular member 82 which is closed at its bottom 84, and extends into and is sealed from the interior of the casing 14. Mounted in the tubular member 82 is the switch 17 which, in the present instance, is provided in a sealed tube 86 of non-magnetic and preferably electrical insulation material, such as glass, for instance (Fig. 4.) Suitably carried in the opposite ends of the tube 86 are contact blades 88 and 90 of which at least the latter is made of non-permanent magnetic material so as to be in magnetic relation with the permanent magnet 74 of the switch-control unit 16 when the latter assumes the operative position shown in Fig. 1. The contact blade 90 is normally resiliently urged into a position in which it is spaced from its companion blade 88, and is drawn into conductive engagement with the latter when in magnetic relation with the permanent magnet 74 of the switch-control unit 16 in the operative position of the latter. The far ends of the contact blades 88 and 90 which project from the adjacent ends of the tube are suitably connected to leads 92 and 94, respectively, which are also connected with a relay 96 underneath the cap 24. The relay 96 may in any suitable manner control the circuit of an electromagnetic filler-valve for the tank T. Since the filler-valve and its circuit do not form part of the present invention, their disclosure is unnecessary.

Also suitably mounted on the support 50, in this instance on the leg 54 thereof, is a permanent magnet 100 which is arranged in magnetically repellent relation with the permanent magnet 74 of the switch-control unit 16 so that the latter is normally urged by magnetic forces into the inoperative position shown in Fig. 3 in which the float portion 76 of the arm 68 bears against the leg 56 of the support 50.

As long as the level of the liquid L in the tank T is below that shown in Fig. 3, the switch-control unit 16 is magnetically urged into the inoperative position shown in Fig. 3. As the tank T is being filled and the level of the liquid therein rises approximately to the level shown in Fig. 3, the float portion 76 of the arm 68 becomes partially immersed in and displaces liquid, so that the float-portion 76 will thereafter rise with the liquid level until the latter reaches substantially the permissible top level shown in Fig. 1 in which the balanced switch-control unit 16 is in its operative position and closes the switch 18 to cause closure of the previously-mentioned filler-valve. Of course, as liquid is being drawn from the tank T and the level of the liquid therein drops, the repellent forces acting between the magnets 74 and 100 will cause the switch-control unit 16 to return to its inoperative position.

The outlets 42 in the casing 14 serve as vents to assure at all times equal air pressure above the liquid levels in the tank T and casing 14 and, hence, the same liquid levels therein. While the switch-control unit 16 may be located anywhere between the outlets 42 and inlets 40 in the cas-

ing 14 as long as the switch 18 is properly co-ordinated therewith, the pivot axis of the switch-control unit is, in the present instance, on a level with the outlets 42 (Fig. 1) so that the tank will have a maximum liquid capacity.

Reference is now had to Fig. 6 in which a modified switch-control unit 16' is shown. Thus, the arm 68' of the instant control unit is, in contrast to the solid float-portion 76 of the earlier-described switch-control unit 16, provided with a hollow float 76' which may be made of two complementary, edge-to-edge joined halves of which one may be integral with or carried by the arm 68'. The pivot axis of the instant control unit, comprising the arm 68' with the float 76' and the permanent magnet 74', passes also substantially through the center of gravity of this unit so that the latter is in any angular position thereof, in substantially neutral equilibrium.

The instant float-switch assembly which is rugged and condensed in construction and generally suitable for installation in liquid tanks of all types, is highly reliable in operation and sensitive in its response to a rising liquid level, as well as unimpaired by even strong liquid-currents thereagainst. Accordingly, the instant float-switch assembly is particularly well adapted for installation in fuel-tanks to exercise a safe and reliable control over the filling of the same even when fuel is forced therein under considerable pressure or at a high flow rate, or both. By virtue of the mounting of the switch-control unit so that the same is in any angular position in substantially neutral equilibrium, the instant float-switch assembly will remain unimpaired even when subjected to shock or vibration, and is, therefore, particularly suited for installation in fuel tanks for air, sea or land carriers which are frequently subjected to these conditions.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. In a float-switch assembly, the combination of an arm pivoted intermediate its ends and having at one side of its pivot axis a float portion; a permanent magnet carried by said arm at the other side of its pivot axis and forming with said arm a switch-control unit, the pivot axis of said arm passing substantially through the center of gravity of said unit so that the latter is in any angular position in substantially neutral equilibrium; an electric switch having companion contact members of which at least one member is of non-permanent magnetic material and in magnetic relation with said permanent magnet throughout a certain rotary range of said unit; and means normally yieldingly urging said unit into a home position spaced at an acute angle from the nearest limit of said certain range thereof.

2. The combination in a float-switch assembly as set forth in claim 1, in which said float portion is an integral solid part of said arm adapted for partial immersion in and according displacement of liquid so that said arm part will rise with a rising liquid level.

3. The combination in a float-switch assembly as set forth in claim 1, in which said means com-

prise permanent magnets of which one is fixedly mounted and the other is carried by said arm.

4. The combination in a float-switch assembly as set forth in claim 1, in which said means comprise permanent magnets of which one is fixedly 5 mounted and the other is carried by said arm and both are in repellent magnetic relation.

5. The combination in a float-switch assembly as set forth in claim 1, in which said means comprise permanent magnets of which one is fixedly 10 mounted and the other is said magnet on the mounted and the other is carried by said arm.

DENNISON H. MACDONALD.
